UNITED STATES PATENT OFFICE

WALTER F. ROLSTON, OF ROCKFORD, ILLINOIS, ASSIGNOR, BY DIRECT AND MESNE ASSIGNMENTS, OF ONE-HALF TO BURSON KNITTING COMPANY, OF ROCKFORD, ILLINOIS, A CORPORATION OF ILLINOIS

KNITTING MACHINE

Application filed December 18, 1925. Serial No. 76,142.

My invention contemplates certain improvements in straight knitting machines prompted in part by observation and study of the Burson type of such machines and in part by the changing trade requirements in respect to stockings, the principal articles knit on these machines. These improvements deal primarily with the frame and needle-bed structure and with the operation 10 of the needles.

Among the objects of my invention are—first, to secure finer and more accurate knitting; secondly, to increase the pattern capacity; thirdly, to give greater accessibility 15 to all needle supporting and operating parts in the bed structure and to permit quick and easy removal of these parts, and especially to permit individual and independent removal of any needle support and its immediate operating parts without disturbing the operative 20 relation, adjustment or set-up of the other similar parts, thus greatly simplifying and reducing the cost of maintenance and repair; fourthly, to enable quick and easy assembling 25 and setting of the various parts in proper operative relation; and fifthly, to enable increased efficiency and longevity of machines of this kind. These and other objects are set forth more in detail hereinafter.

While my improvements are designed primarily for machines of the Burson type and are so illustrated herein, it should be expressly understood that they are in their different phases applicable to other types of 35 straight knitting machines. Because of the nature of these improvements it is believed they will be better understood from the detailed description which follows, this being, of course, merely the preferred embodiment 40 and being subject to modification within the spirit and scope of the appended claims.

Referring to the drawings—

Figure 1 is a plan view of a straight knitting machine embodying my invention;

Fig. 2 is an end elevation of said knitting machine opposite from what is known as the "home end";

Fig. 3 is a perspective view of the frame 50 per se;

Fig. 4 is a fragmentary perspective view on an enlarged scale of certain parts of the bed construction;

Fig. 5 is a vertical section through the front bed taken substantially on the line 55 5—5 of Fig. 1 with the parts in the second level or normal knitting position, described hereinafter;

Fig. 6 is a fragmentary section through the needle cam showing the needle advancing 60 cam in the raised or neutral position with the jack in the second level position referred to;

Fig. 7 is a section similar to Fig. 5 with the parts in the first level or inactive position;

Fig. 8 is a section similar to Fig. 5 with the parts in the third level for advancing one or more special needles, as will be described more fully hereinafter;

Fig. 9 is a vertical section through the needle cams showing the needle advancing cam in the raised position corresponding with the third level position referred to;

Fig. 10 is a detail view of the means for controlling and adjusting the jack holder, 75

described hereinafter;

Fig. 11 is a perspective view of one of the needle supports;

Fig. 12 is a top view of such support;

Fig. 13 is a cross-section through said sup- 80 port taken on the line 13—13 of Fig. 12, and

Fig. 14 is a vertical section through the front bed illustrating the manner in which certain of the parts may be removed.

Frame structure

My invention contemplates the provision of an improved frame preferably an integral casting such as shown in Fig. 3, having transverse end walls or columns 21 and 22 joined and held in rigid spaced relation by longitudinal base parts 23 and longitudinal tie and supporting trusses 24 which underlie each needle bed and serve as a medial support therefor. This construction is especially desirable in that the end walls are maintained in rigid relative relation and the machining of these walls especially for supporting the needle-bed structure and for the pattern cylinder shafts and other parts is great- 90 95 100

ly facilitated and may be accomplished with greater degree of accuracy. The end walls are shaped to provide inclined surfaces 25 and 26 on which are adapted to be mounted and supported the front and rear needle beds respectively, it being noted that each of such surfaces has at its lower end an upstanding lug 27. The frame is further shaped to provide half journal supports 28 for the pattern cylinders, and other bearing supporting brackets for the main shafts which do not enter into the present invention.

When machining said surfaces 25—25 and 26—26, preferably by a planer, a locating recess 30 is cut in each surface for locating the needle-bed end blocks which will be presently described. By reason of the integral construction the said surfaces, recesses and lug surfaces may be accurately machined in aligned planes so as to establish support for the needle-bed structure and to locate such structures in predetermined spaced relation and alignment to a fine degree of precision. The lugs 27 and end faces of the recesses 30 or the equivalent serve to resist certain strains imposed on the needle-bed structure, as for example, the thrust from the pattern cylinder action.

Needle-bed structure

Since the construction of both the front and rear needle-beds is the same, it will be necessary to consider only the front needle-bed which is shown in the drawings.

On the surfaces 25 of the end walls 21 and 22 are mounted end-blocks 29 and 31, the construction of which is best shown in Fig. 4. Each end-block seats against the adjacent lug 27 and has a depending key seated in the frame recess 30 and is clamped to the end wall by screws 32 and 33 so as to be rigidly but removably held in position thereon.

A needle-bed plate designated generally by 34 extending lengthwise of the needle-bed is, in the present instance, cut away at each end as designated by 35 in Fig. 4 to fit in a cutaway 36 in the under side of the adjacent end-block so that each end of said needle-bed plate will fit between the top surface 25 of the adjacent end wall and the under cutaway surface of the end-block. Each end of the needle-bed plate is secured by screws 37 to the adjacent end-block and the whole structure is clamped down onto the end walls by the screws 32 and 33. Thus the end-blocks and the needle-bed plate and all parts carried thereby may be removed as an entirety from the frame by removal of the screws 32 and 33. In the present instance, the needle-bed plate is given further support at a medial point by the truss 24 which has a supporting pad at its center, shown in Fig. 3.

In the preferred embodiment of my invention, the needles do not have bearing support directly on this needle-bed plate but

rather on individual needle supports designated generally by 38 (described in detail hereinafter) which are so mounted on said plate as to permit of individual removal therefrom without disturbing the other needle supports. Said needle supports and the jacks and cooperating parts which likewise will be presently described, are maintained in definite spaced relation by division plates designated generally by 39.

The preferred shape of each division plate is best shown in Fig. 4, each plate being a sheet metal stamping of given gauge appropriate for the gauge of the machine. The top of the bed plate is shaped to interfit with the division plates so as to accurately locate and hold them in predetermined spaced relation and against displacement both transversely and longitudinally of the bed structure. This is accomplished by the provision of an upstanding slotted portion 41 on top at the throat edge of said plate, a similar slotted portion 42 at the opposite or rearward edge and a slotted portion 43 intermediate said portions 41 and 42. The division plates fit in these slots and are further located and held by a key connection comprising a depending key 44 on each division plate fitting in a channel 45 in the needle-bed plate. The slotted portions 42 and 43 are located directly beneath the needle cam mechanism which will be described hereinafter, so that thrust imposed against the sides of the division plates will be directly resisted by reason of this connection with the needle-bed plate.

It will be noted that the division plates at their rearward end project substantially beyond the needle-bed plate and are supported by a rod 46 passing through apertures in said plates, which rod in turn is supported at its ends in the end-blocks. By reason of this construction, the division plates are supported at the rearward end with capacity for flexing laterally so as to relieve the pattern levers, which will be described hereinafter, from strain and wear which might be imposed by variations and irregularities in the pattern plates on the pattern cylinder.

The division plates are securely held at the top by spacing bars 47 and 48 which are slotted on their under side to receive complementary upstanding portions 49 and 51 on the division plates, these spacing bars being suitably secured at their ends to the end-blocks 29 and 31.

The slotted portions 42 and 43 on the needle-bed plate are parallel with but in a plane spaced below the slotted portion 41 to provide space for movement of the jack supports or housings, which will be described later.

Sinker mechanism

The sinkers or presser-hooks 52 may be of any suitable or preferred construction as like-

wise may be the means for actuating them. The sinkers alternate with the needles and their function is well known. They are referred to at present because of their cooperation with the needles in the knitting operation and further because of their cooperation with the needle supports presently to be described which are of a novel construction. The sinkers are, in the present case, mounted in spaced bearing grooves in a sinker bed 53 and are adapted to be projected and retracted at the proper times by a sinker-actuating cam slide 54. Both the sinker bed 53 and the sinker cap 55 are suitably fixed at their ends to the end-blocks 29 and 31.

Needle-support

In prior machines of this type it has been customary to provide a grooved needle-bed on which the needles are supported and moved back and forth in the knitting operation; and in the event that the needle-bearing surfaces wore unevenly or repair of the needle-bed was required it was necessary to disassemble the entire structure and remove the needle-bed. It was also the practice to provide individual needle supports strung upon supporting rods in alternation with division plates, thus providing an individual bearing support for each needle; but in such case it was likewise necessary to disassemble the bed structure in order to remove any needle support. It has been proposed to remedy this condition by the provision of a needle-bearing plate common to all of the needles and removable without tearing down the bed structure in order to replace the worn needle-bearing surfaces; but this practice would necessitate removal of all of the needles and filler springs.

The present invention obviates these difficulties by the provision of individual needle supports any of which may be quickly and easily removed without disturbing the others, thus allowing replacement of any needle bearing surface without affecting the adjustment or setup of the machine.

Another important object in connection with the needle support is that its sinker guiding end is integral with its needle supporting and bearing portion. In other words, I have provided a one-piece needle support and sinker guide. This construction has the further advantage that the sinker guiding end of this support is extended above the needle bearing surface and is grooved to provide side guides for the needle for the purpose of giving lateral support and guidance to the needle.

These improvements are particularly desirable over the prior art in which the practice was to rivet, solder or otherwise secure a supplemental part onto the sinker guiding end of the needle support. In the case of a riveted construction the rivets frequently left

irregular or interrupted guiding surfaces for the sinkers; and in any event, it was practically impossible to secure tight and permanent joints between such supplemental part and the needle support proper, with the result that fibres of the yarn would lodge in these joints and retard the fabric from feeding down; also the side guides would frequently loosen or become roughened and impose uneven bearing or friction against the needle; and, in order to repair it was necessary to take down the entire bed structure to remove the defective needle support.

My improved needle support 38 above-mentioned comprises, in the preferred embodiment, a single piece of sheet steel of a given gage which determines the width of the sinker guiding end 56, reduced in thickness throughout the remainder of its length or at least throughout that portion arranged to be confined between adjoining division plates. In the present instance this reduction in width may be obtained either by a rolling or a grinding operation, it being essential that both sides of the blank be reduced so as to leave a needle bearing surface 57 centrally between the opposed sides 58 which latter serve as guide surfaces for the sinkers. The blank may be suitably shaped as by a stamping operation and an upwardly projecting portion is provided at the sinker guiding end which is grooved longitudinally in alignment with the needle bearing surface to provide side guides 59 adapted to give lateral support and guidance to the needle. The bottom of this groove is preferably arcuate or on a radius in cross-section, as shown in Fig. 13, so as to provide a smooth and self clearing bearing and to allow no square or sharp corners or crevices which might cause undue wear on the needle or admit accumulations of yarn fibres or other foreign matter. This groove also provides bearing support for the needle coplanar with the surface 57. The needle supports are preferably mounted on the needle-bed plate 34 so that they may be individually and independently removed. To this end each support is cut away along its under edge at 61 to receive the upstanding portion 41 of the needle-bed plate and serves to hold the needle support from lengthwise displacement, and also has a hooked portion 62 adapted to engage the front edge of the needle-bed plate which forms an acute angle with the top surface thus serving to retain the needle support from upward displacement. As a further means of holding the needle support in position a rod 63 is passed through an aperture 64 in the support, this rod 63 likewise passing through the division plates. This rod serves to lock the needle support in position and it may be withdrawn from one end of the bed sufficiently to permit removal of any needle support by withdrawal thereof at the throat.

The needle which at present is of the latch type designated generally by 65 rests upon and is supported by the bearing surface 57 which is approximately the length of the 5 needle. The needle is held from displacement by a comparatively light filler spring designated generally by 66 located in the space between the adjoining division plates and being removably retained in position by 10 an upstanding lug 67 engaged in a groove in the underside of the sinker bed 53. By insertion of a suitable gripping tool into the space between the division plates the end 68 of the filler spring may be grasped for removal thereof. A filler spring of this character is claimed in combination with needle operating mechanism in my Patent 1,592,506, 15 issued July 13, 1926.

Jack and jack housing

The jack, designated generally by 69 has the usual hooked end 71 engaging the upturned end 72 of the needle, and has also the usual upstanding lug 73 adapted to be actuated by the needle cams for advancing and retracting its needle to perform the knitting operation when the jack is raised and to be withdrawn to an inactive position in which the jack remains when lowered. The jack rests 25 on a flat bearing surface 74 on a jack support or housing designated generally by 75 which is pivotally mounted at its forward end on a rod 76 in close proximity to the rearward end of the companion needle support. This 30 rod 76 passes through the division plates and provides pivotal support for all of the jack housings and, like the rod 63, it may be withdrawn from the bed structure to permit removal of any jack housing. It is preferred 35 to remove the jack and its needle from the forward end of the bed as shown in Fig. 14 and the jack housing from the rearward end. The needle support may be removed after the needle and its jack have been removed. 40 When reassembling these parts the needle support will first be located and then the jack housing will be inserted from the rear of the bed until its leading end abuts against the inclined cam surface 77 on the needle-bed 45 plate thereby causing such leading end, which is arcuate, as shown, to locate in the complementary arcuate end 78 of the needle support and into registration with the rod 76 so that the jack housing will be strung on 50 the rod when it is inserted.

It will be observed that when the jack is in the retracted position shown in Figs. 5, 60 7 and 8, in which its connection with the needle is in proximity to its pivotal support, it may be swung vertically upon and about such pivotal support to move its lug 73 into and out of the path of the needle cams which function to advance and retract the needle for knitting. In order to positively lower 65 the jack its housing is shaped to provide a

portion 79 which overlies the rearward end of the jack when it is in the retracted position and has a flat bearing surface parallel with the jack-supporting surface 74 so as to provide flat contact of substantial length with the jack. This insures against undue wear between the contacting surfaces and avoids lost motion which might otherwise develop between the jack housing and jack if point contacts between them were employed. The combination of the needle, needle support, jack, and pivoted jack support or housing, with the provision of the full length bearings for the needle and jack on their respective supports is covered in a divisional application, Serial No. 147,675, filed November 11, 1926.

The means for so moving the jack housings for controlling the number of needles in action will now be described.

Pattern mechanism

Any suitable or preferred type or kind of pattern mechanism may be employed for actuating the jack housings or for moving the jacks into and out of operative relation to the needle cams. In the present case, I have shown a pattern cylinder designated generally by 81 for each bed of needles. This pattern cylinder is mounted on a shaft 82 journaled in bearings 80 seated in the lower bearing supports 28 above mentioned, and secured in position by suitable bearing caps. Pattern cylinders of this type are well known and usually include pattern plates which act generally through the intermediary of a pattern lever to raise and lower the jacks and thus to control the number of needles in action and consequently, the shape of the fabric. The mechanism for imparting step-by-step movements to the pattern cylinder is not shown.

In the present case I employ a pattern lever 83 operating between each jack housing and the pattern cylinder. This pattern lever disposed between the adjoining division plates is pivoted on a rod 84 supported on the lowermost end of the division plates and has a pivotal connection with its jack housing. This connection preferably comprises a circular member 85 on the pattern lever fitting in a complementary socket 86 in the jack housing. This circular connection permits positive actuation of the jack housing through a greater arc than with prior constructions; and in the present case I am enabled to move the jack housing to an additional level, or through a greater range of levels than heretofore in machines of this type. The pattern lever has follower projections 87 and 88 adapted to ride on the periphery of pattern plates 89 and 91 respectively and to be actuated by said pattern plates to raise and lower the jack housing. For purpose of clearness the pattern plate 91

for the follower 88 is not shown in Figs. 5, 7 and 9, the plate 91 shown in these figures being for the next adjacent pattern lever.

Referring to Figure 14, I have shown in 5 dotted lines the pattern cylinder 81 in a lowered position permitted by endwise removal of the bearings 80, from which position the cylinder may be moved horizontally to the right for removal from the machine. The top 10 and bottom horizontal dotted lines in this figure indicate the clearance limits and show that the cylinder may be removed independently of the needle-bed structure and the pattern levers associated therewith.

15 *Needle cam mechanism*

The cams adapted to actuate the jack lugs 73 are carried by a cam bar slide 92 mounted in ways on the spacing bars 47 and 48 above mentioned; said slides for both beds of needles together with the sinker actuating slides 54 being connected to a suitable cross-head designated generally by 93 (Figs. 1 and 2) adapted to be reciprocated by operation of the rocker arm 94. The needle cams are of a type well known in this art comprising needle-advancing and retracting cams. It is customary to raise and lower the needle-advancing cam so that when in the lowered position it will actuate any jack lugs which have been raised by the pattern mechanism and in the raised position will pass idly over such raised jack lugs so that they will remain inactive. Any suitable or preferred cam mechanism of this general type, or the equivalent thereof, may be employed with the present invention. The particular cam construction disclosed briefly in the present drawings is shown in full in my patent, above mentioned. It will suffice at 40 present to state that one of the needle-retracting cams is indicated by 95 and the advancing cam by 96. While the retracting cams are at a permanent level the advancing cam 96 is adapted to be raised and lowered upon and with respect to the slide 92, said advancing cam being shown in the raised position in Figs. 6 and 9, and when in the lowered position being substantially flush on its underside with the underside of the cam 95.

50 The cross-head 93 which reciprocates the needle and sinker slides is also connected to a driver head 97 (Fig. 1) which in turn reciprocates a yarn-carrier 98 for distributing the yarn to the needles. The particular form of 55 yarn-carrier and transfer mechanism 99 is unimportant so far as an understanding of the present invention is concerned.

Three level pattern control

60 Heretofore in machines of this type it has been customary to move the jacks by means of the pattern control mechanism to either of two positions, namely, an inactive position and a normal knitting position, the jacks being down in the inactive position and up in

the normal knitting position. The jacks might still, however, remain inactive even though they are in the raised normal knitting position since the needle-advancing cam 96 might be raised so as to clear the jacks in 70 this position, as shown in Fig. 6. In other words, with any given number of jacks in the normal knitting position and with the needle-advancing cam 96 raised the needle cams might be reciprocated any number of 75 strokes without operating the needles, as desired at certain times. If it were desired to bring only one or a comparatively small number of needles into action it would, therefore, with prior constructions, be necessary to 80 lower or throw out of action all of the remaining needles, this being accomplished by lowering the jacks which necessarily would require operation of the jack or pattern levers by the pattern mechanism. It will be 85 manifest, therefore, that wherever it was required to bring a comparatively large number of needles into and out of action at intervals alternating with one or a comparatively small number of needles it was necessary to 90 move a correspondingly large number of parts all actuated from the pattern plates on the pattern cylinder. One illustration is in knitting the widening or fashioned portion at the calf of a stocking in which a single 95 needle is brought into action and the remaining needles are held out of action, the prior practice necessitating that the jacks of said remaining needles be positively lowered to the inactive position and then returned to 100 action on the next round. This obviously imposed considerable wear on all of the parts involved and especially on the cam surfaces and also was a distinct limitation on the pattern capacity of a pattern cylinder.

According to the present invention any jack may be raised to a third level, that is, to a position higher than it would ordinarily occupy in normal knitting, so that the jack or jacks so raised will be actuated by the needle-advancing cam in its raised position, although said cam in such position will not actuate the jacks simultaneously held in the normal knitting position. It follows, therefore, that in the example referred to a single 115 needle such as the widening needle may be operated merely by raising its respective jack to the third level position, leaving any desired number of jacks in the normal knitting position, this being readily distinguished 120 from the prior practice in which it was necessary in order to knit with this single needle to lower all of said remaining needle jacks and raise them again in order to return their respective needles to action.

125 In the present drawings Fig. 7 shows the jack in the lowermost or inactive position, termed the first level; Fig. 5 shows the jack in the normal knitting position termed the second level; and Fig. 8 shows the jack raised 130

to a still higher position for advancing one or more needles, termed the third level, in which the jack lug is adapted to be actuated by the needle advancing cam 96 when the latter is in its raised or neutral position.

The pattern plates may be suitably constructed in furtherance of the foregoing and for purpose of illustration I have shown in Fig. 8 an additional cam lug 101 on the pattern plate 89 and a corresponding depression 102 in the plate 91 to raise the jack to the third level. While mechanism of this character is particularly desirable in the knitting of a fashioned stocking it will be apparent to those skilled in this art that it has its corresponding advantages in the knitting of any fabric, especially one requiring a multiplicity of pattern control movements for moving needles into and out of action. The three level feature is also covered in the divisional application referred to above.

Adjustable jack holder

When the needles or any number of them are in the inactive retracted position, it is desired to hold them from moving forward to prevent them from loosening or changing or varying the tension of the held loops. Heretofore this has been accomplished by engagement of each jack with a fixed abutment on its pattern lever. Such construction is objectionable especially for the reason, among others, that the abutment is fixed and consequently, allows only a single limit for holding its jack. The present invention contemplates the provision of jack-holding means independent of the jack support or housing and of the pattern lever. It further provides for adjustment of said holding means whereby the limit to which the needles may move forward when held in the retracted position may be varied in accordance with changes in tension of the knitting. This is particularly desirable in the knitting of a stocking where the tension is automatically varied at different stages of the knitting.

In the present instance, referring particularly to Figs. 7 and 10, such adjustable or variable holding means comprises a rod 103 passing through and supported by the division plates and having a longitudinal recess or groove 104 the wall 105 of which is undercut to provide a somewhat pointed abutment against which the hooked rearward end 106 of the jack is adapted to engage. The jack housing is cut away at 107 so as not to interfere with the rod 103 when said housing is moved to its different levels. It will be manifest that when the jack is retracted and lowered to the inactive position shown in Fig. 7 its hooked end 106 will engage behind the abutment on the holder or rod 103 and thus be prevented from advancing further than allowed by the position of such abutment. It will also be observed that by imparting ro-

tative movement to the rod 103 the position of its abutment may be changed to advance or retract the effective limit.

Any suitable or preferred means may be employed for imparting such movement, the present invention providing both adjustable and automatically operated means for this purpose. As shown in Fig. 10, an arm 108 fixed to one end of the rod 103 is adapted to be actuated by a cam plate 109 on the pattern cylinder through the intermediary of a cam follower lever 111 and an adjusting screw 112. Suitable means such as a spring 110 may be employed to hold the follower lever 111 against its cam plate. It will be manifest that the cam plate may be so shaped as to rock the jack holder rod 103 at predetermined times to vary the limit referred to, this variation occurring in synchronism with changes in tension which are effected by independent mechanism. By adjustment of the screw 112 the position of the jack abutment may be varied with respect to the throw of the cam plate, thus allowing a fine degree of adjustment. The feature of the adjustable jack holder is also covered in said divisional application.

Tension mechanism

The change in tension of the knitting just referred to may be accomplished by any suitable means and in the present machine is effected by a tension-changing part 113 in the needle cam mechanism above referred to. The construction and operation of this tension-changing device is fully disclosed in my patent above mentioned; and it will be sufficient to state at present that this change is controlled by the pattern cylinder through the operation of a tension lever 114 which is adapted to rock the arm 115 having a channel-shaped adjuster bar 116 which in turn actuates the tension-changing part 113 and imparts certain movement to the needle retracting cams, thereby causing the needles to be retracted to a greater or lesser extent, consequently changing the tension of the knitting. Such tension adjustment is referred to in the present application merely to further illustrate the purpose and advantage of the adjustable jack holder just described.

I claim:

1. In a straight knitting machine, in combination, a bed structure including a needle-bed plate, division plates mounted in spaced relation on said needle-bed plate, said needle-bed plate being slotted on top thereof at three portions at different levels, namely, at its throat end, at its rearward end, and intermediate said ends, for reception of the division plates to hold them in spaced relation and resist lateral strains, top bars slotted on their undersides for reception of the division plates and located forward and rearward of said slotted rearward end and intermediate

portions on the needle-bed plate, end blocks to which said needle-bed and said top bars are fixed, said end blocks being detachably secured to the frame of the machine with the 5 structure assembled thereon, the division plates extending rearwardly beyond the needle-bed plate, and a rod interposed between and mounted on the rearward end of the end blocks, said rod passing through 10 apertures in the division plates and providing support for the rearward end thereof.

2. In a straight knitting machine, in combination, a bed structure including a needle-bed plate, division plates mounted in spaced 15 relation on said needle-bed plate said needle-bed plate being slotted at separate portions on top at its throat end, at its rearward end and intermediate said ends for reception of the division plates to hold them in spaced relation and resist lateral strains, top bars slotted 20 on their undersides for reception of the division plates and located forward and rearward of said slotted rearward end and intermediate portions on the needle-bed plate, 25 and a key connection between each division plate and the needle-bed plate located between the slotted portions at the rearward end thereof.

3. In a straight knitting machine, in combination with a needle-bed and division plates, of a support for each needle mounted on the needle-bed between adjoining division plates and projecting beyond the throat end thereof, said projecting end of each needle 30 guiding support having a needle groove therein, wherein the needle finds guidance to the extreme end of said support.

4. In a straight knitting machine, in combination, a needle-bed, division plates, needle 40 supports on the needle-bed between the division plates, each needle support having an integral end portion provided with a groove at the throat end providing lateral guidance for its needle to the extreme end of said support.

5. In a straight knitting machine, in combination, a needle-bed, division plates, needle supports on the needle-bed between the division plates, each needle support being an integral 50 element and projecting at one end beyond the division plates, the projecting end having a needle groove providing lateral support and guidance for its needle to the extreme end of said support, the adjoining walls 55 of the division plates providing further lateral support and guidance for the needles.

6. In a straight knitting machine, a one-piece needle support having a bearing surface on which its needle rests and is adapted 60 to be reciprocated and having at its end from which the needle is adapted to be projected a groove providing lateral support and guidance for the needle to the extreme end of said support.

65 7. In a straight knitting machine, a one-

piece needle support having a bearing surface on which its needle rests and is adapted to be reciprocated and having at the throat end a groove providing lateral support and guidance for the needle to the extreme end of 70 said support, said grooved end of the needle support having side walls providing sinker guides.

8. In a straight knitting machine, a needle support formed of a single piece of sheet 75 metal of given gage which determines the thickness of the sinker guiding end of the support, said single piece of metal being reduced in width throughout its length except for said sinker guiding end to provide a narrow needle-supporting surface, said sinker guiding end extending above said surface and being grooved to provide a needle bearing surface coplanar with the first mentioned surface and to also provide lateral support and guidance for the needle to the extreme end of 80 said support.

9. In a straight knitting machine, a needle support formed of a single piece of sheet 85 metal of given gage and being rolled to reduce its width except for one end, said reduced portion providing a bearing surface on which a needle is adapted to rest and be reciprocated, and said end portion extending 90 above said bearing surface and being grooved to guide the needle to the extreme end of said support.

10. In a straight knitting machine, an integral support for each needle having a sinker 95 guiding end extending above the needle supporting surface and being grooved to provide lateral support and guidance for the needle to the extreme end of said support.

11. In a straight knitting machine, in combination, a needle-bed plate, division plates in spaced relation on the needle-bed, and needle supports on the needle-bed plate interposed between the division plates, each needle support being an integral element and projecting 105 at one end beyond the division plates, the projecting end being of greater width than the portion confined between the division plates, said projecting end serving as a sinker guide 110 and being grooved to provide lateral support and guidance for its needle to the extreme end of said support.

12. In a straight knitting machine, in combination, a needle-bed plate, division plates, the needle-bed plate being notched along its edge adjacent to the throat to receive and hold the division plates at this end in spaced relation, and needle supports interposed between the division plates, each needle support being cut away on its underside for reception of the needle-bed portion between the adjoining division plates, each needle support being an integral element and projecting beyond the division plates at said throat end, the projecting end of each needle support providing 120 125 130

a sinker guide and having a portion disposed above its needle bearing surface, said projecting portion being grooved to provide lateral support and guidance for its needle to the 5 extreme end of said support.

13. In a straight knitting machine, a needle support in the form of an integral element having a needle bearing surface and at the throat end a portion projecting above said 10 surface and grooved to provide lateral support and guidance for the needle to the extreme end of said support, the bottom of said groove being arcuate in cross-section.

14. In a straight knitting machine, a one- 15 piece needle support and sinker guide having at its sinker guiding end side guides for the needle to the extreme end of said support.

15. In a straight knitting machine, in combination, a needle-bed plate, division plates, 20 and needle supports on the needle-bed plate between the division plates, each needle support having integral therewith at the throat end side walls providing lateral guidance for the needle to the extreme end of said support.

16. In a straight knitting machine, in combination, a needle-bed plate, division plates, needle supports on the needle-bed plate between the division plates, each needle support having integral therewith 25 at the throat and side walls providing lateral guidance for the needle, to the extreme end of said support, said needle supports being individually and independently removable from the needle-bed plate, and a common means for locking all of the needle 30 supports in position and permitting said removal therefrom.

17. In a straight knitting machine, in combination, a needle-bed, division plates, 40 needle supports on the needle-bed plate between the division plates, each needle support having a guide on top thereof for the guidance of the needle to the extreme end of said support, said support being recessed 45 on its underside for reception of an upstanding portion of the needle-bed plate to hold the needle support from lengthwise or upward displacement, and a retaining wire passing through the division plates and 50 needle supports and adapted to be withdrawn for permitting withdrawal of any needle support from its operative position on the needle-bed plate.

18. In a straight knitting machine, in combination, a needle-bed plate, division plates, needle supports between the division plates, each needle support being integral and having a projecting sinker guiding end, 55 said end extending above the needle bearing surface and being grooved to provide lateral support and guidance for its needle to the extreme end of said support, a needle resting on each needle support, a sinker bed, and 60 sinkers mounted on the sinker bed and

adapted to be guided by said sinker guiding ends of the needle supports.

19. In a straight knitting machine, in combination, a needle-bed plate, division plates, needle supports between the division plates, a needle on each needle support, a jack for each needle, a jack support for each jack, a rod passing through the division plates adjacent to the rear end of the needle supports and providing a pivotal mounting 70 for the forward end of each jack support, the needle supports resting on top of the needle-bed plate and said plate being reduced at its top at the rear of said supports to provide clearance for said swinging movement of the jack supports, the needle-bed plate having an inclined surface intermediate the surfaces referred to for guiding the forward end of each jack support into alignment with said rod for locating said end of 75 the jack support when assembling.

20. In a straight knitting machine, a bed structure including a needle-bed plate the top of which has an upper surface adjacent to the throat end, a lower surface at its end remote from the throat, division plates, said upper and lower surfaces of the needle-bed plate being in spaced planes and each having a slotted portion for the reception of and for holding the division plates in fixed space relation, needle supports mounted on said upper surfaces between the division plates, a needle on each needle support, a jack for each needle, and jack supports pivoted adjacent to the rearward end of each needle support 90 and adapted to swing vertically in the space between the division plates afforded by the location of said lower surface of the needle-bed plate.

21. In a straight knitting machine of the character described, a needle bed structure including spaced division plates and needle supports interposed therebetween, each needle support having at its throat end an integral lateral guide for its needle extending 105 to the extreme end of said support.

22. In a straight knitting machine of the character described, the combination of a bed structure including spaced division plates and needle supports interposed therebetween and being individually and independently removable; a needle on each needle support, a jack for each needle, and a jack support for each jack pivoted adjacent 115 to its needle support and adapted to be swung on said pivot to move its jack into and out of an operative position.

23. In a straight knitting machine, a needle-bed plate having a slotted top surface with high forward and low rearward portions for holding division plates in spaced relation, division plates supported upon and held in the slots in spaced relation on the needle-bed plate, a needle support resting 120 upon the needle-bed plate between each di- 125

vision plate and its adjoining division plate and insertible and removable from the front of said plate by endwise movement in a straight line, there being means limiting rearward movement of said support in the insertion thereof whereby to facilitate assembling, and means normally retaining the needle supports in position on the needle-bed plate and permitting removal of any needle support from the needle-bed plate independently of and without disturbing any of the remaining division plates and needle supports.

24. In a straight knitting machine, a needle-bed plate slotted on top at its throat end and similarly slotted at its rear end parallel with and at a level spaced below the slotted throat end for the reception of division plates, division plates mounted on the needle-bed plate held in spaced relation by said slotted portions, needle supports mounted on the needle-bed plate between the division plates, needles on the supports, jacks for the needles, and jack supports each pivotally mounted at its forward end adapted to swing vertically on its pivot through space afforded by the lower level of the rear end of the needle-bed plate, each jack being supported from end to end on its jack support when the latter is operated.

25. In a straight knitting machine, the combination set forth in claim 24, including pattern operated means carried by the division plates for operating the jack supports, and a key connection between the division plates and the needle-bed plate for holding the division plates against lengthwise displacement against thrust from said pattern operated mechanism.

26. In a straight knitting machine, a needle-bed plate slotted on its top for the reception of division plates to hold them in spaced relation, division plates supported on the needle-bed plate, needle supports mounted on the needle-bed plate between the division plates, needles on the supports, jacks for the needles, and jack supports each pivoted at its forward end and adapted to be swung on its pivot to position its jack at different levels, each jack being supported from end to end on its jack support when the latter is operated.

27. In a straight knitting machine, in combination, a needle-bed plate, division plates thereon, individually removable needle supports on the needle-bed plate between the division plates, a needle on each needle support, a jack for advancing and retracting each needle, a jack support for each jack pivotally mounted at its forward end adjacent to the rear end of the needle support, jack operating cams, and a pattern lever for raising and lowering each jack support into and out of operative relation to said jack operating means.

28. In a straight knitting machine, in combination, a needle-bed structure including needle bearing surfaces, a jack for reciprocating each needle, means for actuating the jacks, a support for each jack pivotally mounted at its forward end adjacent to the rear end of its needle supporting surface, and pattern mechanism for raising and lowering the jacks, the needle support, jack support, jack and jack lever between adjoining division plates being removable therefrom independently of the division plates and needle-bed plate.

29. In a straight knitting machine, in combination, a needle-bed plate, division plates, needle supports between the division plates, a needle on each needle support, a jack for each needle, a jack support for each jack, a rod passing through the division plates adjacent to the rear end of the needle supports and providing a pivotal mounting for the forward end of each jack support, and means for swinging the jack supports upon and about said rod to position the jacks at different levels.

30. In a straight knitting machine, in combination, a bed structure including a needle-bed plate, said plate being slotted at different levels at front and rear portions thereof for the mounting of division plates thereon, division plates disposed in the slots in spaced relation on said plate, there being a key connection between each division plate and the needle-bed plate, and one or more top bars slotted on their under sides for reception of the upper edges of the division plates, the needle-bed plate and the top bars being supported at their ends on the frame of said machine.

31. In a straight knitting machine, in combination, a bed structure including a needle-bed plate, said plate having several portions thereof slotted at different levels, the slotted portions being spaced with respect to one another fore and aft of the plate, division plates disposed in the slots in spaced relation to one another, and top bars slotted on their under sides for reception of the upper edges of the division plates, the said top bars being disposed in staggered relation with respect to the slotted portions of said needle-bed plate, and said bars and plate being supported at their ends on the frame of said machine.

32. In a straight knitting machine, a needle-bed plate slotted on top for the reception of division plates, the said plate having a high throat portion and a low rearward portion, division plates mounted in the slots in spaced relation to one another, needle supports mounted on the throat portion of the needle-bed plate between the division plates, needles disposed thereon and having a bearing substantially the full length thereof, jack supports pivoted behind the needle supports between the division plates for vertical piv-

otal movement in the space afforded by the low rearward portion of the needle-bed plate, jacks for the needles bearing on the jack supports substantially their full length, 5 and jack levers pivoted between the division plates at the rearward end of the latter and having pivotal connection with the jack supports for operating the latter.

33. A structure as set forth in claim 32, 10 including one or more top bars slotted on their under sides for reception of the upper edges of the division plates, said top bars being disposed in offset relation to the slotted portions of said needle-bed plate, and 15 said top bars and needle-bed plate being supported at their ends on the frame of the knitting machine.

34. A structure as set forth in claim 32, wherein the needle-bed plate has an inclined 20 intermediate portion between the throat portion and the rearward portion thereof, and wherein the jack supports are pivoted adjacent the upper end of said inclined portion on a cross rod insertible by endwise movement from one end of the needle-bed plate, 25 said jack supports being removable and insertible from the rear of the needle-bed plate and in the insertion thereof being arranged to ride up the inclined portion into position 30 for insertion of the cross rod therethrough.

35. A structure as set forth in claim 32, wherein the needle supports are removably secured in place on the needle-bed plate, as by means of a cross rod insertible endwise 35 from one end of said plate through openings provided in said supports, and wherein the jack supports are pivoted at the rear ends of the needle supports and have the forward ends thereof rounded for reception in the 40 complementarily formed ends of said needle supports, the said jack supports being removably secured in place, as by means of a cross rod insertible endwise through openings provided in the ends of said jack supports from one end of the needle-bed plate.

36. A structure as set forth in claim 32, wherein the needle supports are removably secured in place on the needle-bed plate, as by means of a cross rod insertible endwise 50 from one end of said plate through openings provided in said supports, and wherein the jack supports are pivoted at the rear ends of the needle supports and have the forward ends thereof rounded for reception in the 55 complementarily formed ends of said needle supports, the said jack supports being removably secured in place, as by means of a cross rod insertible endwise through openings provided in the ends of said jack supports from one end of the needle-bed plate, the needle-bed plate having an inclined intermediate portion extending upwardly from the rearward portion thereof to the throat portion and terminating at the rear ends of 60 the needle supports, the jack supports being

insertible and removable from the rear of the needle-bed plate, and in the insertion thereof being arranged to have the front ends ride up the incline into position abutting the rear ends of the needle supports.

37. In a straight knitting machine, the combination with a main frame providing end supporting members, of a bed structure in the form of an assembly arranged to be mounted on said end supports for detachability as a unit, said bed structure comprising end blocks arranged to be fastened removably onto the end supporting members of the main frame, means on said blocks cooperating with said members for positively locating the same thereon, a separate needle-bed plate secured at its opposite ends to the end blocks so as to be demountable with the latter from the frame and accurately located on the frame thereby, said plate having slotted portions at different levels, division plates received in said slots in spaced relation to one another, needle and jack supports inserted between said plates, needles on the needle supports and jacks on the jack supports, and top bars slotted on their under sides for reception of the upper edges of the division plates and having the ends thereof rigidly secured to and definitely located on the end blocks to complete the assembly permitting removal as a unit from the main frame without disturbing the relationship of the elements of said assembly just set forth.

38. In a straight knitting machine, the combination with a main frame providing end supporting members, of a bed structure in the form of an assembly arranged to be mounted on said end supports for detachability as a unit, said bed structure comprising end blocks arranged to be fastened removably onto the end supporting members of the main frame, means on said blocks cooperating with said members for positively locating the same thereon, a separate needle-bed plate secured at its opposite ends to the under sides of the end blocks so as to be demountable with the latter from the frame and accurately located on the frame thereby, said plate having slotted portions at different levels, division plates received in said slots in spaced relation to one another, a cross rod passing through apertures in said plates and supported at its ends in the end blocks whereby to support said plates from the end blocks for the desired rigidity and alignment, needle and jack supports inserted between said plates, needles on the needle supports and jacks on the jack supports, and top bars slotted on their under sides for reception of the upper edges of the division plates and having the ends thereof resting on the tops of the end blocks and rigidly secured to and definitely located thereon to complete the assembly permitting removal as a unit from the main frame without disturbing the relation

of the elements of said assembly just set forth.

39. A knitting machine structure as set forth in claim 23, including a jack for each needle, a jack support therefor, the jack and jack support being disposed between adjoining division plates behind the needle and needle support, the front end of the needle support being rounded and arranged to fit in the complementarily formed rear end of the needle support for pivotal movement relative thereto, and means, such as a cross rod, entered through an opening in the front end of said jack support for retaining the same in position with freedom for pivotal movement.

40. A knitting machine structure as set forth in claim 23, including a jack for each needle, a jack support therefor, the jack and jack support being disposed between adjoining division plates behind the needle and needle support, the front end of the needle support being rounded and arranged to fit in the complementarily formed rear end of the needle support for pivotal movement relative thereto, and means, such as a cross rod, entered through an opening in the front end of said jack support for retaining the same in position with freedom for pivotal movement, the needle-bed plate having an inclined intermediate portion between the high forward and low rearward portions thereof, and said jack support being insertible and removable from the rear of said plate by movement in a straight line, the front end of said support being arranged to ride up the incline in the insertion of said jack support to bring the front end thereof in proper relation to the rear end of the needle support associated therewith, whereby to facilitate assembling.

41. In a straight knitting machine, in combination, spaced division plates, individually removable needle supports between the division plates, a needle on each needle support, a jack for advancing and retracting each needle, a jack support for each jack pivotally mounted at its forward end adjacent to the rear end of the needle support, jack operating cams, and means for raising and lowering each jack support into and out of operative relation to said jack operating means.

In witness of the foregoing I affix my signature.

55 WALTER F. ROLSTON.
